CLAIM

We claim the ornamental design for a lid for container, as shown and described.

DESCRIPTION

FIG. 1 is a perspective view of our design of a lid for container, showing our design in a first configuration;

FIG. 2 is a front view of the lid for container in the first configuration shown in FIG. 1;

FIG. 3 is a left side view of the lid for container in the first configuration shown in FIG. 1;

FIG. 4 is a rear view of the lid for container in the first configuration shown in FIG. 1;

FIG. 5 is a right side view of the lid for container in the first configuration shown in FIG. 1;

FIG. 6 is a top plan view of the lid for container in the first configuration shown in FIG. 1;

FIG. 7 is a bottom plan view of the lid for container in the first configuration shown in FIG. 1;

FIG. 8 is a further perspective view of the lid for container in the first configuration shown in FIG. 1, shown with an exemplary container;

FIG. 9 is a perspective view of our design of the lid for container of FIG. 1, shown in a second configuration;

FIG. 10 is a front view of the lid for container in the second configuration shown in FIG. 9;

FIG. 11 is a left side view of the lid for container in the second configuration shown in FIG. 9;

FIG. 12 is a rear view of the lid for container in the second configuration shown in FIG. 9;

FIG. 13 is a right side view of the lid for container in the second configuration shown in FIG. 9;

FIG. 14 is a top plan view of the lid for container in the second configuration shown in FIG. 9;

FIG. 15 is a bottom plan view of the lid for container in the second configuration shown in FIG. 9; and,

FIG. 16 is a further perspective view of the lid for container in the second configuration shown in FIG. 9, shown with an exemplary container.

The broken lines are shown for illustrating both parts of the article as well as environmental subject matter of an exemplary container. None of the broken lines form part of the claimed design.
